CASH REGISTER

Daniel K. Hughes, Oakwood, Ohio, assignor to
 The National Cash Register Company, Dayton,
 Ohio, a corporation of Maryland

Application May 12, 1939, Serial No. 273,231

4 Claims. (Cl. 235—22)

This invention relates to cash registers and like machines and more particularly to selecting mechanism controlling certain elements of the machine during departmental registering operations.

The principal object of the invention is to provide novel mechanism for superseding the normal automatic selection of certain departmental mechanisms of the register on each machine operation, so that other departmental mechanisms may be selected for operation.

Another object of the invention is to provide drawer selecting mechanism and alarm selecting mechanism controlled through a single differentially settable member.

Another object of the invention is to provide novel departmental mechanism whereby a department drawer and its associated alarm may be selected so as to be operated by the main operating mechanism.

Another object of the invention is to provide novel drawer unlatching means to supersede the departmental unlatching means.

The mechanism is shown embodied in the general type of machine disclosed in United States Letters Patent, No. 2,031,860, issued to Bernis M. Shipley, and more particularly disclosed in the application of Frank Werner for United States Letters Patent, Serial No. 207,244, which issued on April 14, 1942, as Patent No. 2,297,805, and the copending application of this applicant for United States Letters Patent, Serial No. 226,690, which issued on October 6, 1942, as Patent No. 2,297,961, to which patents reference is made.

With these and incidental objects in view, the invention includes certain novel features of construction and combinations of parts, the essential elements of which are set forth in appended claims and a preferred form or embodiment of which is hereinafter described with reference to the drawings which accompany and form a part of this specification.

Of said drawings:

Fig. 1 is a vertical section from front to rear through an amount key bank, as seen from the right, showing the means for transmitting differential data to the totalizers.

Fig. 2 is a detail view of the totalizer selecting and engaging mechanism as seen from the right.

Fig. 3 is a detail view of the totalizer engaging cams.

Fig. 4 is a front view of part of the drawer latch operating mechanism for two drawers located side by side.

Fig. 5 is a detail view in left elevation show-

ing a modified construction of drawer latch operating mechanism for use where two drawers are positioned one on top of the other.

Fig. 6 is a view in rear elevation of the mechanism shown in Fig. 5.

Fig. 7 is a plan view of the control and operating mechanism for the cash drawers and alarms.

Fig. 8 is a view in right elevation of the main operating mechanism and of part of the alarm mechanism.

Fig. 9 is a detail view of part of the mechanism shown in Fig. 8.

Fig. 10 is a right elevation of the departmental or clerk's locks, the operation control lever, and the drawer latch mechanism.

Fig. 11 is a detail of the mechanism used for the automatic selection each machine operation of registering mechanism which normally does not function on each machine operation.

Fig. 12 is a detail view in right elevation of the departmental locks in locked position.

Fig. 13 shows the individual departmental locks in locked position but their locking effect superseded by the control lever.

Fig. 14 is a detail view showing of a part of the lock elements shown in Fig. 12.

Fig. 15 is a detail view of the drawer selecting mechanism.

General description

In departmental cash registers it is desirable that the owner have complete control of all the mechanism and that each clerk have control only over the departmental mechanism assigned to him.

The departmental mechanism of such registers normally includes a drawer, an alarm, a totalizer, and an indicator, together with special counters and printing devices. Of these components of a departmental register, this invention is particularly concerned with the selection and operation of the departmental drawers and alarms as controlled by special departmental locks and as superseded by special control mechanism. Because the machine in which this invention is embodied has been described in detail in the Patents Nos. 2,297,805 and 2,297,961, to which patents reference has been made, only a general description will be given of the main operative features of the machine which are essential to an understanding of this invention.

Framework

The framework of the machine consists of a left vertical frame plate 61 (Figs. 1, 7, and 10) and a right vertical frame plate 62 (Fig. 7)

joined and supported by cross members 63, 64 (Fig. 10) and others not shown, and by various journaled shafts and rods comprising transmission and supporting mechanism. A drawer frame consisting in part of members 66, 67 and 68 (Fig. 10) is joined to the base of the machine and houses two drawers 69 and 70 (Fig. 7) slidably mounted in a manner well known in the art, said drawers being arranged side by side and each normally held in closed position by a latch against the tension of a spring tending to eject it to open position.

Main operating mechanism and differential

The machine in which this invention is embodied is known as the key lever operated type of cash register, having key levers 71 (Fig. 1) pivotally mounted on a key lever shaft 72 journaled in and extending between the frame plates 61 and 62. Loosely mounted, by arms, on rod 73 journaled in and extending between the plates 61 and 62 is a weighted key coupler 74 lying across all the keys to the rear of shaft 72, as shown in Figs. 1 and 10, keeping the keys in their home position as determined by frame member 67. As the forward end of a key is depressed it is rocked about shaft 72 thereby causing the key coupler to be rocked about rod 73. Attached to the right end of the key coupler is a plate 75 (Fig. 8) having pivoted to it, by a stud 84, a double rack 76 cooperating with pinion 77 so as to drive it counterclockwise, as seen in Fig. 8, one complete rotation for each oscillation of the key coupler as actuated by the key on its upward movement and by gravity on its downward movement. Pinion 77 is secured to the main drive shaft 78 as is ratchet 79, which ratchet cooperates with a spring tensioned pawl 80 to prevent retrograde movement of shaft 78. The teeth 81 of the rack, drive the pinion 77 on the upward movement of the key coupler and the teeth 87 drive it on the downward movement of the key coupler, causing said pinion to rotate once for each complete oscillation of the key coupler. Teeth 81 are held in mesh by spring 120, anchored on the key coupler by pivotal stud 85 and on the rack by stud 86, holding the nose 82 against the front edge of guide 83 which, upon reaching the top thereof, passes over to the inner groove of said guide by reason of the pivotal center 84 meanwhile having moved to the other side of the line of centers 85 and 86. Rack member 76 is timed to shift so as to have teeth 87 engage pinion 77 as the key coupler starts back to home position, to complete the rotation of shaft 78.

Those keys performing differential functions are provided with cam slots 387 such as those illustrated in Fig. 1, which slots cooperate with an associated bar 88 fastened to an arm 89 of a segment pivotally mounted on shaft 90. When there are several keys associated with the same bar and its segment, the segment is moved a distance determined by the shape of the cam slot of the operated key. When lateral transmission of the movement of any key actuated segment is desired the segment is furnished with a rear arcuate arm 91 having teeth cooperating with a pinion 92 fastened on an associated shaft 93 journaled in the frame members 64. Thus, for example, if the movement of the key actuated segment just mentioned is to be transmitted laterally, such as to the associated totalizer wheels, a second pinion on shaft 93 cooperates with the toothed arcuate arm 94 of another segment

mounted on shaft 90 which has a forwardly extending toothed segment arm 96 which actuates the selected associated totalizer wheel 98 or 99 or the printing wheel 100. This transmission mechanism is well known and is fully described in Patents Nos. 2,279,805 and 2,297,961, to which reference has been made.

A spring held locking pawl 97 is provided for each segment group, normally locking it by engaging a toe on an arm 103 on one of the segments of a group, preventing positive movement of the whole segment group connected to the associated transmission shaft. When a key is depressed the pawl 97 is disengaged from arm 103 freeing the segment group. As each key operated segment is represented by a segment cooperating with the printing wheels 109, the alining shaft 101, mounted between the printer frames (not shown) acts as a stop to prevent all the segment groups from passing through the zero position. Thus, the segment groups at all times are either locked in the zero position or moved in a positive direction under control of the cam slots in the keys. As department selecting key 105 (Fig. 10) is the only key cooperating with its associated segment 247, the segment is not furnished with a locking pawl, like pawl 97 (Fig. 1), but has an auxiliary cam plate 111 acting therewith, said plate to be later described, by means of a lip 121 preventing positive movement of segment 247 and shaft 192 except when the key 105 or cam plate 111 is operated.

When keys are depressed, the key coupler 74 is caused to rock on shaft 73 the difference between the centers of motion of the keys and the key coupler, causing the key coupler to enter the notch 104 in those keys, locking them on in a manner well known in the art. As the ratchet 79 and pawl 80 (Fig. 8) form a full stroke device the key coupler cannot return to home position until it has been fully oscillated. Any of the keys, such as the "B" clerk's key 105 shown in Fig. 10, may be provided with a cut out portion 106 to cooperate with a special formation 107 of the under side of the key coupler whereby, upon operation of such key, the leading edge of the key coupler jams against the shoulder 108 of the key, stopping further movement of the key. The key coupler having rocked upwardly slightly, and being held in partly raised position by the full stroke ratchet 79, the shoulder 109 of such depressed key is engaged by the edge 110, keeping the key hooked thereon in partly operated position but unable to move further. Keys furnished with such a cut out portion, like the "B" clerk's key just described, are for the purpose of raising the key coupler to a position where other keys may be hooked thereto so that full depression of another key not having the cut 106, as that shown in Fig. 1, will carry all the keys hooked to the key coupler through a full oscillation. The key coupler has a spring latch edge 102 (Fig. 1) to by-pass normal keys onto the partially raised key coupler but which prevents them from being dislodged therefrom. This flexible key coupler arrangement is well known and described more fully in the cited patents.

Totalizer engagement

In the particular embodiment of this invention, herein shown, there are two departmental registering mechanisms each having a totalizer, one of which 98 hereafter being referred to as the "A" totalizer mounted on shaft 145 (Fig. 1), and the other 99 mounted on shaft 146 herein-

after being referred to as the "B" clerk's totalizer.

The machine is constructed to normally engage the "A" totalizer 98 (Fig. 1) on each machine operation if no superseding control is used. Therefore, when the "A" key is depressed it does not function to select the "A" totalizer as that totalizer is normally conditioned to engage on operation of the machine as will be explained. If the "B" key is depressed the "B" totalizer is engaged which necessitates control of the totalizer selecting mechanism by the "B" key. The means for engaging these totalizers selectively will be but briefly described, being fully set forth in the patent and applications cited above.

The "B" clerk's key 105 (Fig. 2) has cooperating therewith the cam plate 111, both key and cam plate being rockably mounted on the shaft 72. A stud 112 extending from the "B" key engages a notch in the cam plate 111 and carries it with the "B" key whenever the latter is operated, but leaving the cam plate 111 free to be moved counter-clockwise without causing the finger operated key 105 to move, as is desirable in operations where the "B" totalizer is conditioned to be selected automatically without depressing the "B" key. The cam plate 111 is notched to receive the key coupler as is the key 105 and is returned to home position after a machine operation by the weight of the key coupler. As the cam plate 111 is rocked counter-clockwise, as seen in Fig. 2, either by depression of the key or by being otherwise rocked automatically, stud 113 extending from cam plate 111 travels upwardly in cam slot 114 rocking the totalizer selecting plate 115 slightly clockwise from the normal position shown (Fig. 2), to select the "B" totalizer for engagement in the ensuing machine operation. As has been explained, the main drive shaft 78 makes one rotation for each machine operation and in so doing rotates a totalizer engaging drive cam 116 mounted thereon so as to rock a plate 117 mounted on shaft 99 first counter-clockwise and then clockwise. Studs 118 and 119, extending from plate 117, engage bifurcations in cam levers 140 and 141 respectively, whose forward ends are pivotally attached to pawls 142 and 143 which are in turn pivotally mounted on one of the totalizer frame plates 144.

The totalizers are mounted on shafts 145 and 146 (Figs. 1, 2, and 3) each carried in a rockable frame, 147 and 148 (Fig. 3) mounted on shafts 149 and 150 supported between frame plates, one of which, 144, is shown. The forward edge of the totalizer selecting plate 115 (Fig. 2) is notched to cooperate with shafts 145 and 146, and with pawls 142 and 143 for controlling the totalizer engagement. In normal rest position, shown in Fig. 2, the plate 115 has a notch opposite shaft 145 and a high place opposite the lower end of pawl 142, a high place opposite shaft 146 and a notch opposite the lower end of pawl 143. On counter-clockwise motion of plate 117, cam lever 140 is rocked clockwise around stud 151, causing stud 152 to be driven downwardly by the cam slot. Stud 152 (Fig. 3) is carried by totalizer engaging lever 153 pivotally mounted on a plate 154 rockably mounted on shaft 99. As stud 152 is driven downwardly a cam slot in the forward end of lever 153 rocks the totalizer frame, by means of shaft 145, in engaging motion toward the differential segments represented in Fig. 1 by reference numeral 96. If the pawl 143 is not blocked from counter-clockwise motion, as illustrated by the notch opposite the low-

er end of pawl 143 (Fig. 2), the motion of cam lever 141 would rock pawl 143 counter-clockwise instead of moving the associated totalizer to engaged position as shaft 146 is blocked by a high place on plate 115. On operation of the "B" clerk's key, the plate 115 is rocked clockwise slightly so as to block out the engagement of the "A" or upper totalizer and causing engagement of the "B" or lower totalizer, by presenting a high place to shaft 145, a notch to the lower end of pawl 142, a notch to shaft 146 and a high place to the lower end of pawl 143.

Plate 154 (Fig. 3) may be rocked counter-clockwise along with plate 117 (Fig. 2) to prevent the engaging of either totalizer by causing pin 155 to be lowered into slot 156 and slot 159 (Fig. 2) thus operatively connecting the two plates together. This result, accomplished by mechanism not shown, is accomplished by rendering the downward motion of studs 152 ineffective by causing the pivot points 157 and 158 to move downward. This result, desirable in transactions where money is paid out, is not a part of this invention, and the mechanism for accomplishing this result will not be described; however, reference may be had to Patent No. 2,297,961, before cited, for the details of this mechanism.

Drawer mechanism

Slidably mounted side by side in the base of the cabinet, are two cash drawers 69 and 70 (Figs. 7 and 10) each latched in closed position, against the ejecting force of a spring tensioned arm 122, by latches 171 and 172 (Figs. 7 and 10) engaging latch plates 173 and 174 on the respective associated drawer. Latch 171 is secured to frame supported shaft 175 (Figs. 7 and 10), and latch 172 is secured to frame supported shaft 176 (Fig. 7). Rocking either shaft clockwise, as seen in Fig. 10, releases the associated drawer to the spring action of its ejecting mechanism. Each latch is provided with a pawl 178 to hold the latch in unlatching position until the drawer is closed. This pawl is provided to require the drawer to be closed before the machine can again be operated when the control lever 170 is placed in the proper position as will be explained in connection with the controls and interlocks. Referring to the right drawer, as shown in Fig. 10, as an example, when the latch 171 is operated, by the rocking of shaft 175 clockwise, the drawer is released and pawl 178 is allowed to rock counter-clockwise, in response to the tension of spring 179, until it is positioned to be engaged by shoulder 180 of the latch by the contact of roller 181, with the arcuate surface 182. Under these conditions the latch cannot resume its normal latched position until pawl 178 is knocked back by the latch plate on the closing of the drawer to the position shown in Fig. 10. Thus, shaft 175 is held rocked clockwise from normal position until the drawer is closed. This holding of shaft 175 in rocked position will, if the control lever 170 be properly positioned, prevent the machine from being operated.

Loosely mounted on the left end of shaft 175 is an arm 183 (Figs. 4 and 7) to which is pivotally attached a link 184 (see also Fig. 15) having a hook 185 at its upper end to engage the main drive shaft 78 so as to be vertically slidable thereon between collars secured on said shaft. Extending from the right side of the hook is a stud 186 (Figs. 10 and 15) adapted to be engaged 75 by the periphery of a cam 187 having a high point

188 adapted to strike and lift the stud 186 near the end of each machine operation thus raising the link 184. Secured to the inner ends of shafts 175 and 176 (Figs. 7 and 10) are arms 190 and 189 respectively, arm 189 having pivoted thereto link 195 and arm 190 having pivoted thereto link 196, each link having a hooked top to slidably engage shaft 78 in a manner similar to link 184. Link 184, a driving member, is selectively coupled either to link 195 controlling the latch for the drawer 13, or to link 196 controlling the latch for drawer 69, by means of a plate cam 191 (Figs. 10 and 15) selectively positioned by means of the department control mechanism to be described. Cam 191 secured to frame supported transmission shaft 192 (Figs. 7, 10, and 15) cooperates with the bifurcated portion of a lever 193 pivotally mounted by a pin 194, secured thereto, on link 184. The lower end of lever 193 ends in a hook 193 adapted to engage a stud 197 extending from link 196 when the lever 193 is rocked clockwise by cam 191 as seen in Fig. 10. On the left end of the pin 194 is secured a hook 294 adapted to engage a stud 199 on link 195 when the lever 193 is rocked counter-clockwise by cam 191. Therefore, the position of the cam 191 as positioned by shaft 192 determines which one of the two links 195 and 196 will be coupled to the link 184 to be raised thereby, and consequently determines which drawer shall be unlatched on the operation of the machine. Shaft 192 is positioned by the department key 105 and cam plate 111 (Figs. 2 and 10) as will be described.

Figs. 5 and 6 show a modified form of the drawer unlatching means adapted to registers having one drawer above the other. In this construction the "A" drawer 200 is provided with a latch 201 pivoted to a frame member 202 which latch is connected by an auxiliary link 203 to link 196 through pivotal stud 204 extending from an arm 205 pivoted on frame supported stud 206.

The latch 207 for the "B" drawer, also pivoted on stud 206, is connected directly to link 195 by stud 208. Driving link 184 is guided by being pivoted to rock arm 209 also pivoted on stud 206.

Alarm mechanism

Associated with each departmental mechanism of the machine is an alarm bell, the "A" department bell 216 (Figs. 7 and 8) being securely mounted on stud 217 secured to frame plate 62 by screw 220, the bell being separated from the frame by a washer 221. On a sleeve 222 on stud 217 is mounted a hub 219 having secured to it a lever 223 and the "B" departmental bell 218 eccentrically mounted. Arm 223 (Figs. 8 and 9) is bifurcated to engage a stud 224 extending from the forwardly extending arm of a segment 225 rotatably mounted on shaft 90. The articulate rear arm of segment 225 has teeth 226 (Fig. 8) cooperating with pinion 227 (Figs. 7 and 8) secured on shaft 192 which shaft as before stated also positions the drawer selecting cam 191. In rest position, as shown in full line in Fig. 7, the strike rim of the "A" bell 216 is slightly farther from the axis of the bell hammer 228 than is the strike rim of the "B" bell, but by making the right portion of the bell hammer of larger diameter than the left portion, upon movement of the hammer toward the bells only the "A" bell is struck. However, when the eccentrically mounted "B" bell is rotated by movement of segment 225 to the position shown by the broken line, the strike rim of the "B" bell is enough

nearer the axis of hammer 228 to allow the left half of the hammer stud to strike the "B" bell without the right half of said stud striking the "A" bell.

5 The bell hammer is actuated by the movement of the key coupler in the following manner. Pivotally mounted on the plate 75 (Figs. 7 and 8) fastened to the key coupler is a lever 229 normally held in the position shown in Fig. 8 by spring 230. As the key coupler is raised, pivotal stud 231 is carried counter-clockwise around rod 73 as a center. A positionable guide member 232 (Figs. 7 and 9) when in the position shown in Fig. 9 is adapted to be contacted by an ear 233 on lever 229 (Figs. 7 and 9), as the key coupler is rocked upward, causing lever 229 to be moved clockwise (Fig. 9) with relation to plate 75 against the tension of spring 230. As the ear 233 reaches the top of the guide 232 the lever 229, no longer being under restraint thereof, responds to the tension of spring 230 tending to move it to its normal position relative to plate 75 and, in so doing, the lever overthrows its normal position by reason of its inertia, carrying 20 the bell hammer 228 held thereby against the selected bell. After striking the bell the spring 230 returns the lever to home position thus allowing the bell to vibrate undamped by contact with the hammer.

25 30 Guide member 232 may be moved rearwardly which removes it from the path of ear 233 thereby allowing lever 229 to move with the plate 75 undisturbed relatively thereto, which consequently fails to produce the necessary motion for the hammer to contact the selected bell.

Secured to rod 73 (Fig. 8) is a lever 234 having its other end pivotally connected to a link 235 the outer end of which bears the guide member 232. An aperture in frame plate 62 provides 40 entrance of guide member 232 to the inside of the frame where it may co-operate with ear 233. A bearing stud 236 on link 235 (Fig. 7) extending through a guide slot in frame plate 62 limits the extent of movement and supports the free end of link 235. By turning rod 73 (Figs. 7 and 9), by means of a hand lever 237 secured thereto, the bell may be made operative or inoperative. To control this bell muffler mechanism by the 45 50 control shaft 238 (Figs. 7 and 8) to be fully described, said shaft has secured to its right end a cam 239 (Fig. 8) having cam follower 240 (Figs. 8 and 9) cooperating therewith. Cam follower 240 is secured to lever 241 pivotally mounted on frame plate 62 by stud 242 in such a manner that clockwise movement of cam 239 rocks lever 241 counter-clockwise and counter-clockwise movement of cam 239 rocks lever 241 clockwise. Lever 241 in its most counter-clockwise position 55 60 is shown in Fig. 9, in which position the rear end of lever 241 blocks movement of link 235 holding it in forward position where guide 232 enables the hammer to strike the selected bell. If the link 235 is in its rearmost position the 65 end of lever 241 will lock the hammer mechanism in disabled position.

Drawer and alarm selecting mechanism

The machine of the present embodiment having 70 two departmental registering mechanisms denominated for this disclosure as the "A" clerk and "B" clerk departments, there are provided an "A" clerk's key 243 (Fig. 7) to be operated on transactions conducted by the "A" clerk and a "B" clerk's key 105, previously mentioned, to be

operated on transactions conducted by the "B" clerk.

The "A" totalizer being normally engaged as explained, the machine is also arranged to normally operate the "A" drawer latch and to ring the "A" alarm bell, even though the "A" clerk's key is not used. As is shown in Fig. 15 the hook 198 normally engages the stud 197 on link 196 so that no differential rotation of shaft 192 is needed, on operations of the "A" department, to select the "A" drawer. The "A" alarm bell 216 (Fig. 7) is in position to be struck if there is no movement of shaft 192. Therefore it is not necessary for the "A" key to be used for the selection of the "A" department of the register.

If the "B" department is to be selected the "B" key must ordinarily be used, the exception to be later explained. The auxiliary plate 111 (Fig. 2), rocked through stud 112 on operation of the "B" key 105, has a cam slot 245 which cooperates with a bar 246 projecting from a segment 247 (Figs. 7 and 10) which is rockably mounted on shaft 90 and which has a toothed rear projecting arm cooperating with pinion 248 pinned to shaft 192, said shaft being turned a certain fixed angle on depression of the "B" key and then turned back to home position as the "B" key returns home.

When shaft 192 is turned by operation of the "B" key the cam 191 (Fig. 15) is turned with it which rocks lever 193 disengaging hook 198 from stud 197 and engaging hook 294 with stud 199, thus connecting link 184 to the link 195 so as to cause the "B" drawer to open when cam 187 lifts the link 184 on operation of the machine.

Shaft 192 has fastened to its right end the pinion 227 (Figs. 7 and 8) which cooperates with segment 225 rockably mounted on shaft 90. Segment 225 in being rocked moves the "B" bell to a position where it may be struck as before explained.

Thus, operations of the machine involving the movement of cam plate 111 select the "B" totalizer, the "B" drawer opening mechanism, and the "B" alarm mechanism.

Departmental locks

Loosely mounted on shaft 275 is a lever 276 (Figs. 10, 11, 12, and 13) having a notch 277 on a forwardly extending arm, and having a second arm 278 (Fig. 11) extending to the right which is riveted to a lever 279 (Figs. 7 and 10) also loosely mounted on shaft 275. Lever 279 has a downwardly extending arm forming a hook 280 adapted to engage a stud 281 (Fig. 7) on the "B" key when said lever 279 is rocked clockwise from the position shown in Fig. 10 to that shown in Fig. 12, and to release said stud 281 when rocked counter-clockwise as shown in Figs. 10 and 13. The position of stud 281 is represented diagrammatically in Figures 10, 11, and 12. When the hook 280 engages the stud 281 the "B" key is held thereby in home position and cannot be depressed. Also rockably mounted on shaft 275 is a lever 282 having a hook 283, formed by its downwardly extending arm, adapted to engage a stud 284 on the "A" key. Said stud 284 is also represented diagrammatically in Figs. 10, 11, 12, and 13, being located to the left of stud 281 as shown in Fig. 7. Lever 282 has a cam slot 285 (Fig. 11) accommodating a stud 286 secured to a lever 287 pivotally mounted on a stud 288 secured to the left frame plate 61. When lever 282 is rocked clockwise, hook 283 engages stud 284, as shown in Fig. 11, preventing the "A" key from

being depressed, and when rocked counter-clockwise frees stud 284 permitting the "A" key to be depressed. The forward end of lever 287 has a notch 289.

- 5   Mounted on a lever 290 (Figs. 10 and 13), which lever is itself rockably mounted on a stud 291 secured to the left frame plate 61, are two barrel locks, one of said locks 292 (Fig. 10) being associated with the "B" key and the other of said locks 293 being associated with the "A" key. Secured near the rear end of the barrel of lock 292 is a collar 394 (Figs. 10, 11, and 14) having a nose 295 on its periphery. Secured near the rear end of the barrel of lock 293 is a collar 297 similar to collar 394 having a nose 298 on its periphery. The rear end of the barrel of lock 292 terminates in a stud 296 (Fig. 14) and the rear end of the barrel of lock 293 terminates in a stud 299. A slide 300 bifurcated at its lower end (Fig. 11) 20 to straddle stud 299 and having an elongated slot 301 to accommodate stud 296 is permitted vertical motion limited by slot 301. Slide 300 has a pin 304 secured to it which may be engaged on one side or the other by the nose 295 of collar 294 so that when the barrel of lock 292 is turned clockwise, as seen in Fig. 14, slide 300 will be forced to its lowest position and when the barrel of lock 292 is turned 360 degrees counter-clockwise slide 300 will be forced to its highest position. In a similar manner the nose 298 of collar 297 cooperates with pin 305 on slide 302 to raise and lower it. Slide 302 is mounted on stud 299 by means of slot 270 which permits and limits its vertical motion, said slide having a bifurcated 25 top end 271 to straddle and be guided by stud 296. The fact that the collars 394 and 297 require that the barrels of the locks be turned 360 degrees to function fully causes the keys to be in the same withdrawing position, either the clockwise or the counter-clockwise position. Ears 306 and 307 (Fig. 13) bent over on lever 290 hold the slides 300 and 302 in position on the studs 296 and 299. It will be noted that the aforementioned movements of slides 300 and 302 are relative to the locks 292 and 293. Slide 300 has an ear 308 (Fig. 11) which engages notch 277 and slide 302 has an ear 309 which engages notch 289, so that relative movement of slide 300 with respect to shaft 275 and of slide 302 with respect to stud 288 will move the respective associated levers 279 and 282 either to locking or unlocking position with their associated studs 281 or 284 to lock or unlock the respective clerk's key. 30   It will be observed that lever 290 (Fig. 10), upon which the locks 292 and 293 and the slides 300 and 302 are mounted, is normally held clockwise on pivotal stud 291 by spring 310 until shoulder 311 strikes shaft 275. In this clockwise position the levers 279 and 282 will engage the studs on their associated key when both slides 300 and 302 are in their up position. Under these circumstances if lever 290 is rocked counter-clockwise by the operator, the slide 300 will move relatively to shaft 275 and slide 302 will move relatively to stud 288 causing levers 279 and 282 to rock counter-clockwise freeing the "A" and "B" keys. Thus, the rocking of lever 290 counter-clockwise until stopped by frame member 63 will 35 supersede the locking action of locks 292 and 293. Whenever the "A" lock 293 is locked causing lever 287 (Fig. 11) to be rocked clockwise around stud 288, a stud 312 engages a camming notch 313 in a lever 314 pivotally mounted on a stud 315 40 carried by the cam plate 111 of the "B" key (see 75

Fig. 10), so that lever 314 is rocked slightly counter-clockwise around stud 315 positioning shoulder 317 over the key coupler thereby causing every operation of the key coupler to carry with it the "B" key cam plate 111 to operate the "B" differential segment 247. However, if the "A" lock 293 is locked and the lever 290 is pulled down to supersede the action of lock 293, lever 287 is rocked counter-clockwise around stationary stud 288 allowing spring 316 to unhook shoulder 317 from the key coupler so that both "A" and "B" transactions may be registered.

Control lever

A single control lever 170 (Figs. 7, 10 and 13) pivotally mounted on stud 318 projecting leftwardly from the left frame 61 has a lock 319 on its forwardly projecting arm to lock it in one of five positions, diagrammatically shown in Fig. 13, which lever by means of the toothed arcuate rear arm cooperates with a pinion 320 (Fig. 7) secured to shaft 238 to turn it differentially. The different positions of the lever 170 will be referred to as the "open drawer," "closed drawer," "lock register," "total," and "reset" positions.

Secured on the shaft 238 is a cam 321 (Figs. 7, 12 and 13) having a rim 322 adapted to block the movement of stud 338, carried by an arm of lever 290, preventing the lever from rocking counter-clockwise from normal when the stud is outside the rim, and preventing the lever 290 from returning to normal position if the stud is inside the rim. The rim is broken away so that the stud may be moved from outside to inside or vice versa, whenever the shaft is in the "reset" position as determined by the control lever. In this manner only the person having a key to the control lever lock may, by shifting the lever to reset position, supersede the control of clerk's individual locks 292 and 293.

Another cam 323 (Figs. 7 and 10) is secured on shaft 238 to cooperate with a stud 324 on a lever 325 rotatably mounted on rod 73. The rearmost end of lever 325 is bifurcated to engage a stud 326 on lever 327 rotatably mounted on shaft 90. A spring 328 anchored to ears on levers 325 and 327 tends to rotate lever 325 counter-clockwise on its axis and lever 327 clockwise on its axis, which movement is limited by the engagement of stud 324 with the rim of cam 323. Also rotatably mounted on shaft 90 is a lever 329 held against stud 338 by a spring 331 causing lever 329 to move with lever 327 positively in a clockwise direction and resiliently in a counter-clockwise direction. The bent over rear end of lever 329 forms an ear having a notch 332 (Fig. 7) cut therein, adapted to cooperate with a bent over ear 333 (Figs. 7 and 10) on cam 187 secured on the main drive shaft 78. With the machine at rest, the cam 187 is positioned as shown in Fig. 10, and as shaft 78 rotates counter-clockwise the ear 333 will have to move through notch 332 or by-pass on one side or the other of the bent over ear 335 or the machine will not operate due to the blocking of the main drive shaft. As the control lever 170 positions cam 323 it therefore controls the locking of the machine. In the "open" drawer position of lever 170, cam 323 is positioned so the ear 333 passes through notch 332. In the closed drawer position the ear 333 will pass over ear 335, if the drawers are closed, and in all other positions of lever 170 the ear 333 will be blocked by ear 335 thus preventing a registering operation of the machine. The resilient

connection between levers 327 and 329 prevents strain on the parts if the control lever is moved while ear 333 is in the path of movement of ear 335.

- 5 There is provided, as before mentioned, means for making it necessary for both drawers to be closed before the machine is operated if the control lever has been previously set at the "closed drawer" position. This position of the control lever rocks lever 327 clockwise so ear 333 rides over the top of ear 335 if the drawers are closed. It has been explained how, when a drawer is open, the latch is held in unlatched position by pawl 178 as shown in Fig. 10, until the drawer is closed. This holding up of the latch causes the corresponding one of the two links 195 and 196 to be kept in the position to which it was raised by link 184 on the drawer opening operation. Each of the links 195 and 196 has on the front edge of its upper end a notch which is adapted, when said links are in normal position and the control lever is in "closed drawer" position, to engage stud 336 (Figs. 7 and 10), projecting from lever 327, so that when either of the links 195 or 196 is raised on drawer opening operations, the stud 336 will be raised, rocking lever 327 slightly counter-clockwise from the position it has assumed upon lever 170 being moved to "closed drawer" position and instead of the ear 333 passing over the top of ear 335 it is blocked by the upper half of ear 335 thus locking the machine. As soon as the drawers are closed, lever 327 drops back to the "closed drawer" position where the ear 333 will pass over the top of ear 335 when an operation of the machine is commenced.

- On the control shaft 238 being turned to the position it assumes when control lever 170 is in the "reset" position, the cam 323 rocks lever 327 to its most counter-clockwise position which causes stud 336 to forcibly contact the top of the notches in the links 195 and 196 lifting said links and causing both drawers to be unlatched without movement of the main operating means. In this position of the control lever, the lower half of ear 335 blocks ear 333 locking the machine against operation. Thus, when the control lever is moved to position where the totalizers are to be reset the drawers automatically open as they cannot thereafter be opened by a machine operation, the registering mechanism being locked. When the control lever is in "lock register" position the upper half of ear 335 blocks ear 333 preventing operation of the register.
- 55 The cam 239 (Fig. 8) fastened to shaft 238 and controlling the bell muffler lock, is turned to unlocking position when the shaft 238 is in reset position thus making the bell muffler mechanism dependent on the operator's power to control lever 170.

Operation

In departmentalized cash registers, such as the one herein disclosed where the departments represent clerks, it is desirable for the employer to have complete access to all the registering functions while each clerk has access only to his own departmental registering mechanism. In the disclosed machine having two registering departments this desirable result is accomplished by giving the "A" clerk a key to the lock 293 and the "B" clerk a key to the lock 292, while the employer retains the key to the control lever.

If the "A" lock 293 is unlocked and the "B" lock 292 is locked, upon operation the machine

will register in the "A" totalizer, the "A" drawer will open, and the "A" alarm will sound with or without the use of the "A" clerk's key, but the "B" department cannot be selected for registering. If the "B" lock is also unlocked the "A" department may be operated as before, but if the "B" clerk's key is used the "B" department will be selected for that one operation. If only the "B" lock is unlocked the "B" department is always selected with or without the use of the "B" key and the "A" department cannot be selected.

If the control lever is moved to reset position so lever 290 (Fig. 10) can be rocked counterclockwise and then the control lever moved to "open drawer" or "closed drawer" position to hold lever 290 in its rocked position, the machine may be operated whether the locks 292 and 293 are locked or unlocked, the "A" department always being selected with or without the use of the "A" clerk's key unless the "B" clerk's key is used.

The control lever will also give the employer control over the closed drawer mechanism and the alarm mechanism, neither of which may be made operative or inoperative without having control lever 170 unlocked and movable.

While the form of mechanism herein shown and described is admirably adapted to fulfill the objects primarily stated, it is to be understood that it is not intended to confine the invention to the one form or embodiment herein disclosed, for it is susceptible of embodiment in various forms all coming within the scope of the claims which follow.

What is claimed is:

1. In a cash register having two drawers and a main operating mechanism, the combination of a member oscillated up and down at each operation of the main operating mechanism; a latch for each drawer; a link associated with each latch, movement upwardly of either of which links unlatches its associated latch; and a double hook pivoted to the oscillating member which when moved in one direction couples one of said links to the oscillating member for upward movement and which when moved in the opposite direction couples the other link to the oscillating member for upward movement.

2. In a cash register having two drawers and a main operating mechanism, the combination of a member oscillated vertically on each operation of the main operating mechanism; a link mounted on each side of the oscillating member each link being associated with a drawer and adapted to be vertically oscillated; an unlatching means for each drawer operated by upward movement of the link with which it is associated; a stud on each link; a double hook pivotally mounted on

the oscillating member so as to engage the stud on one of the links when in one position so as to couple said link to the oscillating member for upward movement and movable to another position to disengage said stud and to engage the stud on the other link so as to couple said other link to the oscillating member for upward movement.

3. In a cash register having two drawers each normally latched in closed position by an individual latch but disposed when unlatched to be ejected to open position, the combination of a main operating means; a shaft rotating once during each operation of the main operating means; a cam secured on said shaft; a vertically movable member which is moved by said cam first up and then down on each rotation of the shaft; a vertically movable link positioned on each side of said vertically movable member, each of said links by vertical movement unlatching one of the drawers; a stud on each link; a double hook pivoted to the vertically movable member said hook having two positions in one of which positions it is operative to couple to said member one of said links by means of the associated stud and operative in the other position to couple said member to the other link by means of the associated stud causing vertical movement in the coupled link on vertical movement of the member to unlatch the latch of its associated drawer; a second shaft rotatable to one of two positions; a cam secured on said second shaft which when the said second shaft is in one position engages the double hook with one of the studs and when the said second shaft is in the other position engages the double hook to the other stud; a key; and key actuated means to turn the said second shaft differentially to one or the other of the two positions.
4. In a cash register having two drawers normally latched in closed position, the combination of means for unlatching each drawer comprising a vertically movable link for each drawer operative on upward movement to unlatch its associated drawer; a lever; means to move both links upwardly by moving said lever; a main operating means; an oscillating member moved up and down on each operation of the main operating means; and a movable coupling means comprising a double hook mounted on the oscillating member and adapted to couple one or the other of said links to said member to cause the oscillating member to move said coupled link upwardly with it said link being selected by moving said coupling means to render one or the other parts of the hook effective.

DANIEL K. HUGHES.

CERTIFICATE OF CORRECTION.

Patent No. 2,338,942.

January 11, 1944.

DANIEL K. HUGHES.

It is hereby certified that error appears in the above numbered patent requiring correction as follows: In the grant, line 1, and in the heading to the printed specification, line 3, residence of inventor, for "Oakwood, Ohio" read --Dayton, Ohio--; page 1, first column, line 30, for "Patent No. 2,297,805" read --Patent No. 2,279,805--; page 2, first column, line 19, strike out "mounted" first occurrence; and that the said Letters Patent should be read with this correction therein that the same may conform to the record of the case in the Patent Office.

Signed and sealed this 14th day of March, A. D. 1944.

Leslie Frazer

(Seal)

Acting Commissioner of Patents.
